DESIGN FOR A BOTTOM STOP FOR SLIDE
FASTENERS

Noel J. Poux, Meadville, Pa., assignor to Talon,
Inc., Meadville, Pa., a corporation of Penn-
sylvania

Application August 24, 1939, Serial No. 86,859

Term of patent 14 years

To all whom it may concern:

Be it known that I, Noel J. Poux, a citizen of the United States, residing at Meadville, in the county of Crawford and State of Pennsylvania, have invented a new, original, and ornamental Design for Bottom Stops for Slide Fasteners, of which the following is a specification, reference being had to the accompanying drawing, forming a part thereof.

In the drawing:

Fig. 1 is a front perspective view of a bottom stop for slide fasteners, showing my new design from one angle;

Fig. 2 is a view similar to Fig. 1 of the bottom stop shown in Fig. 1, as seen from an opposite direction;

Fig. 3 is a face view of the rear of the bottom stop shown in Figs. 1 and 2; and

Fig. 4 is an end view of the bottom stop shown in Figs. 1, 2 and 3.

I claim:

The ornamental design for a bottom stop for slide fasteners, substantially as shown.

NOEL J. POUX.
